GAME BOARD

James R. Ball, 512 J.M.S. Bldg., South Bend, Ind.

Filed Feb. 16, 1961, Ser. No. 63,957

Term of patent 7 years

(Cl. D34—5)

FIG.2

FIG.1A

FIG. 1B

The dominant feature of my design resides in the portion shown in full lines.

I claim:

I claim:

The ornamental design for a game board, substantially as shown and described.
